Primary Examiner — Elizabeth J Oswecki*Assistant Examiner* — Lacey Chey Bowman*(74) Attorney, Agent, or Firm* — Knobbe, Martens, Olson & Bear, LLP(57) **CLAIM**

The ornamental design for a camera enclosure as shown and described.

DESCRIPTION

FIG. 1 is a top plan view of a camera enclosure showing my new design;

FIG. 2 is a front view thereof;

FIG. 3 is a left side view thereof;

FIG. 4 is a back view thereof;

FIG. 5 is a right side view thereof;

FIG. 6 is a bottom plan view thereof;

FIG. 7 is a front right side perspective view thereof;

FIG. 8 is a front left side perspective view thereof;

FIG. 9 is a back left side perspective view thereof; and,

FIG. 10 is a back right side perspective view thereof.

The broken lines shown in the figures are for the purpose of illustrating portions of the camera enclosure that form no part of the claimed design.

1 Claim, 10 Drawing Sheets(56)
